United States Patent Office

Des. 181,956
Patented Jan. 28, 1958

181,956

PROXIMITY WARNING INDICATOR

John F. Beckerich, Dallas, Tex.

Application September 10, 1956, Serial No. 42,885

Term of patent 14 years

(Cl. D52—1)

FIG. 1

FIG. 2

Figure 1 is a front elevational view of a proximity warning indicator showing my new design, and

Figure 2 is a perspective view thereof.

The dominant features of the design reside in the portions shown in full lines.

I claim:

The ornamental design for a proximity warning indicator, as shown and described.
